MACHINE FOR PRODUCING GEARS

Werner Forster, Zurich, Switzerland, assignor to
 Maag-Zahnräder und-Maschinen A. G., Zurich,
 Switzerland

Application January 7, 1939, Serial No. 249,786
 In Germany January 7, 1938

5 Claims. (Cl. 90—9)

This invention relates to a machine for producing gears on the rolling principle of the type disclosed in the re-issued patent to Maag No. 14,908 or in the German Patent No. 395,662.

- 5 This machine includes a rotary controller which performs one complete revolution during a cycle of operation of the machine and governs the functions of the machine. The machine is equipped with a shaping tool of rack form. The 10 controlling mechanism of the machine ordinarily functions to cause the machine at any cycle of operation to work in one tooth space of the blank only. The blank performs a rolling motion extending over one tooth space at any cycle. 15 If it is desired to extend the rolling motion within a cycle over two or more tooth spaces in order to have the rack-shaped tool work with a larger section of its length in favor of a more uniform wear, special gear transmissions must 20 be provided. This operation results in a gain of time since the operation required after any indexing motion for taking up the lost motion of the rolling elements need be performed once only for a plurality of teeth. These advantages, 25 however, are connected with a disadvantage. If the rolling motion in a cycle of operation is to be extended over a plurality of tooth spaces without increasing the rolling speed, it is necessary that the speed at which the rolling members 30 are driven be reduced.

An object of the present invention is to avoid these disadvantages. According to a feature of the invention, a timed mechanism is coordinated to the means driving the rotary controller and 35 is adapted to temporarily disable these driving means in order to arrest the rotary controller during any cycle of operation for a certain period of time. The machine is thus caused during this period of time to continue the operation 40 which it performed at the instant at which the controller was arrested. In this manner, it is possible to extend the rolling operation over any desired number of tooth spaces within a cycle and to cut the teeth therein without varying the 45 normal speed of the controlling operations.

The drawings illustrate two embodiments of a machine for cutting spur gears.

Fig. 1 is an elevation of a gear shaping machine embodying the invention, partly shown in 50 section;

Fig. 2 is a plan view of the work table, the gearing being diagrammatically indicated;

Fig. 3 is an elevation of the timed mechanism;

Fig. 4 shows an elevation of a gear grinding 55 machine similar to Fig. 1, and

Fig. 5 is a diagrammatic representation of the motion of the work slide during a cycle of operation.

The frame 1 of the machine (Fig. 1) is provided with horizontal guide ways on which a slide 2 is movable. On this slide there is mounted a rotary table 3 capable of turning about a vertical axis. This table carries the blank 4 which is rigidly connected therewith in axial registry. A column of the frame 1 is provided with vertical guide ways on which a reciprocatory ram 5 is movable carrying the rack-shaped tool 6. The ram is moved up and down through a crank mechanism comprising a crank shaft 9, a crank disc 8 and a connection rod 7. The shaft 9 is driven from a motor through a clutch (not shown) and a pair of gears 10, 11. From the crank shaft 9 (Fig. 2) an auxiliary drive is derived through a pair of bevel gears 12, 13 serving the purpose of performing the rolling motion. The bevel gear 13 is connected with a shaft 14 diagrammatically indicated in Fig. 2 and the shaft 14 carries a crank mechanism 15, 15a of adjustable stroke including a connection rod 16 adapted to reciprocate a ratchet pawl 18 (Fig. 1) engaging a ratchet wheel 17.

In lieu of the ratchet pawl other suitable elements 18a acting in one way only may be employed. In this manner, a shaft 19 connected with the ratchet wheel 17 is intermittently 30 driven. This motion is transmitted from the shaft 19 through a pair of meshing gears 20 and 21 to an auxiliary shaft 22. This shaft may be driven in the opposite direction by auxiliary means to be described later. It operates a pair 35 of gears 23, 24. The hub of the gear 24 is loosely mounted on a shaft 25 and is constructed as a double clutch 26, 26a, each end of this clutch being adapted to engage a member 27, or 27a respectively, which is slidably mounted on the 40 shaft 25 but secured against relative rotation thereto. The teeth of these clutches are facing in opposite directions, whereby the shaft 25 may be driven in either direction of rotation of the gear 24. By means of these clutch members, the 45 shaft 25 may be stopped in one direction of rotation, for instance, at the beginning and at the termination of the operation on a blank, by disengagement of these clutches through manual operation of an actuating lever 28.

By means of gear transmissions 29, 30, or 31, 32, 33 respectively, the rotation of the shaft 25 is transferred to a gear shaft 34 and thence through a further pair of gears 35, 36 to the rotary controller formed by a cam drum 37. 50 55

Two clutch members 38 and 39 having teeth of opposite direction are interposed between the shaft 25 and the two gears 29 and 31 loosely mounted thereon. The teeth of the clutch members 38 and 39 engage complementary teeth provided on the hubs of the gears 29, 31. Depending on the rotation of the shaft 25 one of these gears is driven while the clutch of the other gear slips.

10 The motion of the shaft 22 is transferred through a pair of bevel gears 40, 41 and the table shaft 42 to a pair of bevel gears 43, 50. From this pair of bevel gears, the rolling motion of the machine is derived. For this purpose, the slide 2 mounted on straight horizontal guide ways has a nut 45 attached to it engaging a screw spindle 44 which is rotatably mounted and secured against longitudinal displacement. The rotary work table 3 mounted on the slide 2 has a worm wheel 46 attached to it engaging a worm 47 adapted to impart a rotary motion to the work table. The displacement of the slide 2 and the rotation of the work table are so proportioned that the blank performs a rolling motion relative to the rack-shaped tool.

15 Two groups of change gears 48 and 49 connect the spindle 44 and the shaft of the worm 47 with the bevel gears 43, 50. The change gears 48 and 49 are selected to meet the requirements depending on the number of teeth and the pitch of the gear to be cut.

20 When the slide 2 arrives at the end of its rolling stroke, the reciprocatory motion of the tool-carrying ram 5 is interrupted and the slide 2 together with the work table 3 and the blank 4 is returned moving backwards the entire rolling stroke along a straight line, while the rotary motion of the table 3 is interrupted. The ram 5 is stopped by action of a cam 51 of the controller drum 37, the cam acting through a follower 52 and a lever 53 on a link 54 disengaging a clutch (not shown) interposed between the driving motor and the crank shaft 9. Thereupon another cam 55 of the controller actuates a follower 56, thereby putting an auxiliary driving mechanism for shaft 22 in operation. This auxiliary driving mechanism comprises a clutch member 57 mounted on the shaft 22 for common rotation therewith and longitudinal displacement thereon and adapted to engage a clutch member 57b, at the same time disengaging a clutch member 57a. On the clutch member 57b there is provided a gear 58 meshing with another gear 59. The clutch member 57b is freely rotatable on the auxiliary shaft 22, whereas the gear 59 is fast on a shaft 60 of a pulley 61 continuously driven by the driving motor of the machine.

25 When the crank shaft 9 was stopped by action of the controller 37, the intermittent actuation of the shaft 19 ceased. The direction of rotation of the shaft 60 is such that upon engagement of the clutch members 57 and 57b the auxiliary shaft 22 is driven from the shaft 60 in the opposite sense. This has the effect of driving shaft 42 and the pair of bevel gears 43, 50 in the opposite direction whereby the movement of the slide 2 is reversed. Similarly, the rotary motion of the table 3 being effected through the change gear 49, an auxiliary shaft 66 and a pair of gears 67, 68 from the pair of bevel gears 43, 50 is likewise reversed. The gear 67 is freely rotatably mounted on the shaft 66 and is adapted to be connected therewith for common rotation through a pair of clutch members 65. Upon reversal of the gears 43, 50 the rolling motion of

30 the blank is reversed by the simultaneous motion of the slide 2 and the table 3 in reversed direction over a short distance. Then, a cam 62 of the controller 37 arrives in position to act on a follower 63 disengaging the clutch 65 through a linkage 64, whereby the rotary motion of the table 3 is interrupted while the slide 2 continues its translatory movement. Therefore, the table 3 continues its return movement without any rolling motion thus indexing the blank in a known manner. Then, the cam 55a of the controller arrives in position to act on the follower 56 thereby re-engaging the clutch 57, 57a and thus terminating the return movement of the blank. A short rolling motion in working direction serving the purpose of taking up any lost motion while the tool is still at rest, is subsequently effected by the action of a cam 83 of the controller 37. This cam actuates a follower 84 mounted on a lever 85 shifting a clutch member 88 which is keyed to a shaft 87 for common rotation therewith. This shaft is continuously driven from the shaft 60 through the gear 59 and a gear 86 meshing therewith. The clutch member 88 is shifted into engagement with a clutch 89 integral with a gear 90 loosely mounted on shaft 87 and meshing with a gear 91 which is integral with the gear 21 and the clutch member 57a. Therefore, the engagement of the clutch members 88 and 89 causes the shaft 22 to be driven at a reduced speed in the positive rolling direction, whereby the rolling motion is initiated at a reduced speed to take up any lost motion.

35 A feature of the present invention resides in the provision of means for temporarily stopping the controller 37, if it is desired, to extend the rolling motion within the cycle of operation over n tooth spaces. The period of time during which the controller is thus stopped may be chosen as required by the length of the rolling motion. When the rolling motion shall be extended over n tooth spaces, the controller is stopped for $n-1$ tooth spaces.

40 To this end, the two clutch members 38 and 39 on the shaft 25 are disengaged at a predetermined instant. For this purpose, each clutch member is provided with an annular groove engaged by studs 69 carried by a bifurcated lever 70 provided with a follower 71. The two followers 71 engage cam faces of a rotatable cam plate 72. This cam plate is pivotally mounted and may be rocked through a link 73 carrying a follower 74. This follower is operable by a timed mechanism. The timed mechanism is in permanent driving connection with the shaft 25. For this purpose, this shaft is geared with a worm 77 through a pair of bevel gears 75, 76. The worm engages a worm wheel 78 attached to a shaft 79. On this shaft 79 there is firmly mounted a disc 80 shown in Figs. 2 and 3 which constitutes the timed mechanism. The disc is provided with a plurality of circumferentially distributed holes marked by suitable numbers as shown in Fig. 3. Stops 81 and 81a may be selectively inserted in these holes. These stops are formed with cam grooves 82 and 82a which are inclined relative to the plane of the disc 80. Upon rotation of the disc the grooves 82 and 82a are adapted to engage over the follower 74 thus longitudinally shifting the link 73. The shaft 25 and the disc 80 geared thereto rotate alternately in opposite directions. Depending on their setting on the disc, the stops 81, 81a engage the follower 74 at different times to engage and disengage the clutch members 38 and 39. In this manner, the controller 37 may be

temporarily stopped during the cycle of operation at various instants and for different periods of time.

The operation is as follows: When the machine is set up for an operation in which a single tooth space only is worked upon at any cycle, the cycle is comprised of the following operations diagrammatically indicated in Fig. 5:

I. The controller 37 is intermittently rotated step by step through $\frac{1}{10}$ revolution while the blank is rolled forward by action of the crank shaft 9 operating the ratchet mechanism 15, 16, 17. During this operation the reciprocating shaping tool works on the blank within a single tooth space, while the cam 51 remains in engagement with the follower 52. Upon completion of this partial revolution of the controller the cam 51 disengages the follower 52 thus stopping the crank shaft 9 and arresting the tool. Immediately afterwards the cam 55 engages the follower 56 shifting the same towards the right thus disengaging the clutch member 57 from the clutch member 57a and engaging it with the clutch member 57b, whereby the rotation of shaft 22 is reversed.

II. During the following $\frac{1}{20}$ revolution of the controller the blank is rolled backwards. Then, the cam 62 arrives in engagement with the follower 63 moving the same towards the right, whereby the clutch 65 is disengaged terminating the rotation of the work table 3.

III. During the following $\frac{1}{10}$ revolution of the controller the blank performs a translatory return motion by movement of the slide 2 without rotation of the table 3. At the end of this step the cam 62 disengages the follower 63 thus re-engaging the cam 65.

IV. During the following $\frac{1}{20}$ revolution of the controller the blank performs a return rolling motion. At the end of this step the cam 55a engages the follower 56 rocking it towards the left thus disengaging the clutch member 57 from the clutch member 57b and re-engaging it with the clutch member 57a. At the same time the cam 83 engages the follower 84, whereby the clutch members 88 and 89 are engaged. This has the effect of reversing shaft 22.

V. During the subsequent $\frac{1}{10}$ revolution of the controller the blank is rolled forward. At the end of this step the cam 83 disengages the clutch members 88 and 89; at the same time, the cam 51 causes the driving clutch of the cam shaft 9 to be re-engaged, whereby shaft 22 will be driven at normal speed thus resuming the intermittent rolling motion and the cutting operation of the step No. I. The cycle of operation is now completed.

If it is desired to set up the machine for a rolling motion in which a larger number of tooth spaces are worked upon within a single cycle, for instance, nine tooth spaces, I provide means for temporarily stopping the controller in the position A (Fig. 5) during the step I shortly after the commencement thereof. For this purpose, the stops 81, 81a on the disc 80 are inserted in holes which are nine units apart. When the point A is reached in the performance of period I of the cycle, the stop 81 engages the follower 74 thus causing the cam plate 72 to be rocked in clockwise direction thereby disengaging the clutch members 38 and 39. Consequently, the controller 37 stops while the rolling motion derived from shaft 22 is continued. After eight tooth spaces have been worked upon by the tool at normal speed, the stop 81a on the disc 80 arrives

in engagement with the follower 74 and shifts the link 73 thus re-engaging the clutch members 38 and 39. Consequently, the controller resumes its rotary motion controlling the subsequent operations as above described.

Early in the period III of the cycle at the instant A₁ (Fig. 5) the stop 81 provided with the cam groove 82 has returned to engagement with the follower 74 disengaging the clutch members 38, 39 and stopping the controller. While the controller is at rest, the return motion of the slide 2 continues through eight tooth spaces and the disc 80 keeps on to turn until the stop 81a engages the follower 74 and thus re-engages the clutch members 38 and 39 putting the controller 37 in operation. After the slide 2 has moved the remaining ninth tooth space, the controller 37 acts on the mechanisms above described to continue the cycle of operation through the periods IV and V as above described, whereupon the new cycle of operation commences.

In the embodiment above described the tool is formed by a rack-shaped planing tool. However, a shaping tool in form of a single tooth may be used for cutting large gears. In this event, a very extended rolling motion is required. Moreover, I may substitute two dished grinding discs 6a for the rack-shaped tool, these discs being driven by two motors 6b as shown in Fig. 4. These grinding discs work in the same manner as a shaping tool formed with a single tooth. In these events, it is particularly desired to temporarily arrest the controller during the extended rolling motion or return motion. This has the advantage that the rolling motion and the return motion of the blank may be extended without modifying the speed of the rolling motion of the blank and of the operation for taking up the lost motion. Therefore, these operations may be performed at the ordinary speed.

With the use of a tool formed with a single tooth or of grinding discs as described, the operation differs from that above described in that the indexing motion is to be limited to a single tooth space. The rolling motion and the return motion, however, extend over a plurality of tooth spaces, for instance, nine tooth spaces per cycle. The limited indexing motion requires that on the return stroke the rotation of the table 3 is interrupted for a single tooth space only. For this purpose, the disc 80 (Fig. 2) is angularly displaced on its shaft 79 through a predetermined small angle and attached to the shaft 79 in its new position. This has the effect that the clutch members 38 and 39 are disengaged by the stop 81 at the instant B₁ of the period II of the cycle of operation (Fig. 5). Hence, the controller remains at rest during the return rolling motion extending through eight tooth spaces while the control disc turns through the angular distance of the stops 81 and 81a, whereupon the operation is terminated in normal manner indexing the blank one tooth space. In the period I of the cycle the corresponding stoppage of the drum commences at the instant B.

The timed mechanism for arresting the controller may be also used in cutting gears having a small number of teeth and a large pitch. In work of this type the machines used prior to my invention have an extremely fast rolling motion. In order to avoid this disadvantage, the stops 81, 81a may be inserted in the holes 1 and 9 of the disc 80 (Fig. 3). At the same time, the change gears 48, 49 (Fig. 2) are so chosen that the spindle 44 and the worm 47 are driven at a ninth

of the normal speed, whereby the rolling motion is slowed down as desired.

While I have described my invention by reference to a specific embodiment thereof, I wish it to be understood that it is not limited to the details thereof but is capable of numerous modifications which will readily occur to anyone skilled in the art. This applies particularly to the specific design of the timed mechanism for temporarily stopping the controller.

What I claim is:

1. A machine for producing gears operating on the rolling principle, comprising a rack-shaped tool, a work carrier, a mechanism causing said work carrier and said tool to perform, within a cycle, a relative rolling motion, a return motion and an indexing motion, a rotary controller governing the operation of the machine being adapted to perform one complete revolution during a cycle of operation, means driving said controller, and a timed mechanism coordinated to said driving means and adapted to temporarily stop said controller in any cycle of operation thus causing the machine during the temporary stoppage of said controller to continue the operation performed by the machine at the instant of the interruption of the revolution of said controller.
2. A machine for producing gears operating on the rolling principle comprising a rack-shaped tool, a work carrier, a mechanism causing said work carrier and said tool to perform, within a cycle, a relative rolling motion, a return motion and an indexing motion, a rotary controller governing the operation of the machine being adapted to perform one complete revolution during a cycle of operation, means driving said controller, and an adjustable timed mechanism coordinated to said driving means and adapted to temporarily stop said controller for a variable period of time in any cycle during said rolling motion thus enabling the machine during the temporary stoppage of said controller to continue said rolling motion for a period of time variable by adjustment of said timed mechanism.
3. A machine for producing gears operating on the rolling principle comprising a rack-shaped tool, a work carrier, a mechanism causing said work carrier and said tool to perform, within a cycle, a relative rolling motion, a return motion and an indexing motion, a rotary controller

governing the operation of the machine being adapted to perform one complete revolution during a cycle of operation, means driving said controller, a timed mechanism coordinated to said driving means and adapted to temporarily stop said controller in any cycle thus enabling the machine during the temporary stoppage of said controller to continue the operation performed by the machine at the instant of the interruption of the revolution of said controller, and adjustable means for variably determining said instant.

4. A machine for producing gears operating on the rolling principle, comprising a rack-shaped tool, a work carrier, a mechanism causing said work carrier and said tool to perform, within a cycle, a relative rolling motion, a return motion and an indexing motion, a rotary controller governing the operation of the machine being adapted to perform one complete revolution during a cycle of operation, means driving said controller including a clutch, a rotary support, means for rotating said support, and adjustable abutments on said support adapted to disengage and engage said clutch to temporarily stop said controller in any cycle of operation thus causing the machine during the temporary stoppage of said controller to continue the operation performed by the machine at the instant of the interruption of the revolution of said controller.

5. A machine for producing gears operating on the rolling principle, comprising a rack-shaped tool, a work carrier, a mechanism causing said work carrier and said tool to perform, within a cycle, a relative rolling motion, a return motion and an indexing motion, a rotary controller governing the operation of the machine being adapted to perform one complete revolution during a cycle of operation, means driving said controller including a clutch, a rotating shaft, a support mounted on said shaft, and adjustable abutments on said support adapted to disengage and engage said clutch to temporarily stop said controller in any cycle of operation thus causing the machine during the temporary stoppage of said controller to continue the operation performed by the machine at the instant of the disengagement of said clutch, said support being angularly adjustably fixed to said shaft to variably determine the instant of disengagement of said clutch.

WERNER FORSTER.
